UNITED STATES PATENT OFFICE.

WILLIAM COBURN, OF SEATTLE, WASHINGTON.

OILING SYSTEM.

Application filed November 2, 1922. Serial No. 598,495.

To all whom it may concern:

Be it known that I, WILLIAM COBURN, a citizen of the United States of America, and resident of the city of Seattle, in the county 5 of King and State of Washington, have invented certain new and useful Improvements in Oiling Systems, of which the following is a specification.

My invention relates to an attachment for 10 internal combustion engines in the form of an oiler, which may be either the principal oil circulating medium or a device which is auxiliary to the main oil circulation system.

My invention is particularly useful, upon 15 Ford automobiles, for the Ford engine depends for lubrication upon oil thrown centrifugally from a rotating flywheel, this oil being carried by the circulating pipe, which receives it, to the timing gears positioned 20 slightly in advance of the first crank dip in the engine pan. It often happens that this circulating pipe, which is wholly within the engine casing, becomes clogged and the first indication thereof is, perhaps, a burned out 25 main bearing. Further, the regular oiling system becomes ineffective when the engine and the car are tilted upward at the front end, as when climbing a long hill, and oil is then not delivered to the first crank dip of 30 the engine pan.

It is an object of my invention to remedy these defects; to provide an auxiliary oiling system which can be relied on to lubricate the engine independently of the main oil circulating system, and which is easily accessible 35 to determine if the oil is circulating properly; and one which will regulate the amount of oil fed to the forward end of the engine pan in accordance with the inclination 40 of the car—that is, which will increase the extra oil supply as the car is inclined upward.

An important object of my invention is to provide such an auxiliary oiler which is 45 easily accessible for adjustment.

A further object is the provision of such an oiler in which advantage is taken of all possible pressure due to difference of levels, and in addition, of the slight extra head due 50 to the pressure caused by the centrifugal force by which the oil is delivered to the oiler.

Another object is the provision of a simple, inexpensive and easily connected oiler.

My invention comprises those novel parts 55 and combinations thereof which are shown

in the accompanying drawings, described in the specification, and particularly defined by the claims terminating the same.

In the accompanying drawings I have 60 shown my invention in the form which is now preferred by me.

Figure 1 is a perspective view of a Ford engine showing my oiler attached thereto.

Figure 2 is a partial elevation and partial 65 section of the strainer and the connection to the engine pan.

Figure 3 is a section through the flywheel casing, showing the manner of taking off the oil. 70

Figure 4 is a section through the valve and gravity controlled regulator therefor.

Figure 5 is a plan view of a detail of the regulator.

In a Ford engine the oil is contained in 75 the engine pan 10 at such a level that when the engine is level it will rise to the proper depth in the various crank dips, 11, 12 and 13. If, however, the engine is tilted up at the front as when climbing the hill, the crank 80 dip 11, under the forward or No. 1 cylinder, quickly becomes empty and no more oil can flow thereinto. At this time, and by the use of my device, an increased flow of oil occurs through the auxiliary oiler to compensate for the normally decreased oil in the 85 first crank dip 11.

The flywheel 15 runs in oil contained within the casing 14, and at a point at or near its top the casing 14 is bored and tapped to receive a nipple 2, having a lip 21 which extends well into the casing 14, and which is positioned to receive oil centrifugally thrown from the flywheel 15. The engine pan 10 at a point slightly above and ahead of the first 90 crank dip 11 is also bored and tapped to receive a nipple 3, to which, externally of the engine pan 10, is secured a trap 31 having a removable cover 32 and containing a screen 33. A conduit 23 connects the nipple 2 and 100 the trap 31. Obviously, the position of the trap 31 in the conduit 23 is unimportant, and it might well be placed at some other point therein, but in order to secure the advantage of all possible sources of pressure, I prefer 105 that it be positioned as described.

At some point in the conduit 23, preferably before it has inclined downwardly to any great extent, and preferably adjacent the nipple 2, I connect a stand pipe 4. This is shown 110 as connected to one branch of a T-fitting 24, the other branches of which are connected in

the conduit 23. The upper end of the stand pipe may be suitably supported, as by a bracket 41 which is secured to the engine 1. The upper end of the stand pipe 4 is open.

5 Within the T-fitting 24 is formed a valve seat 25, and a valve 5 is movable therein to vary the effective area of the conduit. A stem 51, preferably of heavy piano wire, extends upwardly from the valve 5 through the 10 stand pipe 4, and at its upper end 52, above the stand pipe, it is threaded. To this end 52 is secured some suitable gravity-controlled means for regulating the oil flow in accordance with the inclination of the engine.

Such gravity-controlled means, as shown herein, comprise a lever pivoted at 61 to a bracket 60 and having a downwardly extending arm or pendulum 62, with a weight 20 6 thereon, and having a laterally extending arm 65 which is suitably connected to the valve stem 51. The end of the arm 65 is shown as bored at 66, and in this bore is pivoted an ear 67, the latter being provided with 25 an aperture which receives the end 52 of the valve stem. Adjusting nuts 68, 69 are threaded on the end 52 above and below the ear 67, and by their adjustment may vary the normal effective opening past the valve 5.

30 Oil thrown from the flywheel 15 has a certain momentum which is turned into a slight hydrostatic head in the standpipe 4. The upper end of the standpipe is always above the level of the nipple 2, and the oil therein will not overflow. The valve 5, when open, permits oil to rise above it in the standpipe, or to flow therefrom to the nipple 3. Thus 35 the oil pressure on the nipple 3 is normally the sum of the head due to the difference in level of itself and nipple 2, plus the head resulting from the oil's centrifugal force. The standpipe 4 thus serves to conserve this head for use when required.

45 As the engine's front end is raised, the pendulum arm 62 swings backward, and the valve 5 is opened more. As the oil drains from the first crank dip 11, extra oil is supplied thereto through the conduit 23. As 50 the engine tilts in the opposite direction, and the oil runs back into the dip 11, the pendulum arm 62 swings forward, and more nearly closes the valve 5.

A new engine requires considerable oil, and the adjusting nuts 68 and 69 would 55 therefore be set to give a normal large opening of the valve 5, on the level. As the engine wears, less oil can be supplied, hence the valve opening must be normally less. By reason of the convenient location of these 60 adjusting nuts, adjustment thereof is quickly and easily accomplished, and is not liable to be deferred or forgotten.

65 The connection between the upper end of the valve stem 51 and the arm 65, as described, permits the valve stem to pivot on

the arm 65 readily, and its inherent flexibility throughout its length, permits it to take up lateral motion, without a slotted connection.

What I claim as my invention is:

1. A lubricating attachment for automobile engines having rotating oil-carrying members enclosed within a casing, comprising an oil receiver entering said casing, a conduit leading from said receiver to a lower portion of the engine, a standpipe connected into said conduit, a valve at the foot of said standpipe controlling the rate of flow of oil through the conduit, a stem therefor extending through the upper end of the standpipe, and gravity-controlled means for regulating the closing or opening of said valve in accordance with the inclination of the automobile.

2. A lubricating attachment for automobile engines having rotating oil-carrying members enclosed within a casing, comprising an oil receiver penetrating said casing to receive oil centrifugally thrown by said oil-carrying members, a conduit leading from said oil receiver downwardly to a lower portion of the engine, a valve in said conduit controlling the rate of flow of oil through the conduit, an externally extending stem for said valve, and gravity-controlled means connected to said stem, and operable as the engine is tilted forward to close the valve, and as it is tilted rearward to open the valve.

3. A lubricating attachment for automobile engines having rotating oil-carrying members enclosed within a casing, comprising an oil receiver penetrating the upper portion of said casing to receive oil centrifugally thrown by said oil-carrying member, a conduit leading from said oil receiver downwardly and forwardly to a lower portion of the engine, a valve in said conduit controlling the rate of flow of oil therethrough, an external upwardly extending stem for said valve, a lever having a downwardly extending weighted arm and a laterally extending arm, and means connecting said laterally extending arm to the upper end of said stem, whereby said valve may be closed as the engine is tilted forwardly, and opened as it is tilted rearwardly.

4. A lubricating attachment for automobile engines having rotating oil-carrying members enclosed within a casing, comprising an oil receiver penetrating the upper portion of said casing to receive oil centrifugally thrown by said oil-carrying member, a conduit leading from said oil receiver downwardly and forwardly to a lower portion of the engine, a valve in said conduit controlling the rate of flow of oil therethrough, an external upwardly extending stem for said valve, a lever having a down-

wardly extending weighted arm and a laterally extending arm, an apertured ear pivotally secured in said laterally extending arm, the upper end of said valve stem being threaded and received in the aperture of said ear, and adjusting nuts threaded upon said stem both above and below said ear to vary the normal effective opening of said valve.

- 10 5. In a lubricating attachment for an automobile engine, for the purpose specified, in combination with an oil conduit connecting the forward and rear ends of the crank case chamber of said engine, and a valve controlling the flow of oil through said conduit, a gravity-controlled and pivoted arm extending longitudinally of the engine and substantially horizontal, a flexible valve stem extending upward adjacent said arm, 20 an ear pivoted in said arm, and means for securing the upper end of said valve stem in said ear.
6. In a lubricating attachment for automobile engines, for the purpose specified, in combination with an oil conduit connecting the forward and rear ends of the crank case chamber of said engine, and a valve controlling the flow of oil through said conduit,

a gravity-controlled laterally extending arm pivoted to swing in a plane extending longitudinally of the engine, a flexible valve stem extending upward adjacent said arm, an ear pivoted in said arm, the upper end of said valve stem being threaded, and said ear being apertured to receive said threaded end, and nuts threaded thereon above and below said ear to adjustably secure the valve stem in said ear.

- 15 7. In a lubricating attachment for automobile engines, for the purpose specified, in combination with an oil conduit connecting the forward and rear ends of the crank case chamber of said engine, and a valve controlling the flow of oil through said conduit, a stand-pipe connected in said conduit and 25 open at its upper end, a gravity-controlled laterally extending arm pivoted to swing on a plane extending longitudinally of the engine, a flexible valve stem extending upward through said stand-pipe adjacent said arm, 50 an ear pivoted in said arm, and means for securing the upper end of said valve stem in said ear.

Signed at Seattle, King County, Washington, this 27th day of October, 1922.

WILLIAM COBURN.
